UNITED STATES PATENT OFFICE.

EDWIN E. RUSHTON, OF LOS ANGELES, CALIFORNIA, ASSIGNOR TO EMILIE HAND, OF LOS ANGELES, CALIFORNIA.

LIQUID-FUEL SMELTER.

1,314,150.

Specification of Letters Patent. Patented Aug. 26, 1919.

Application filed July 15, 1918. Serial No. 244,873.

To all whom it may concern:

Be it known that I, EDWIN ERNEST RUSHTON, a citizen of the United States, residing at Los Angeles, in the county of Los Angeles, State of California, have invented new and useful Improvements in Liquid-Fuel Smelters, of which the following is a specification.

This invention relates to smelters for ores of various kinds; and the object of the invention is to provide a liquid fuel smelter capable of handling various kinds of ores and capable of carrying on efficiently the desired smelting operations. It is also an object to provide an improved form of smelter furnace with certain improved features of construction and operation as hereinafter set forth.

The invention is best embodied in an inclined smelting chamber in which the ore is first heated and the metal then melted; and in the combination therewith of a system of air heating by regenerative means. This air heating system preferably takes the form of a double air heater whose parts are used alternately.

Other objects and features of the invention, and the invention itself, will be best understood from the following description in detail of preferred forms of furnace embodying the invention, reference for this purpose being had to the accompanying drawings in which—

Figure 1 is a vertical longitudinal section of a preferred form of my improved furnace; Fig. 2 is a cross section taken as indicated by lines 2—2 on Fig. 1; Fig. 3 is in part a plan and in part a section taken on line 3—3 of Fig. 2; Fig. 4 is a vertical section taken on line 4—4 of Fig. 1; Fig. 5 is a vertical section taken on line 5—5 of Fig. 1; Fig. 6 is a longitudinal section of a modified form and arrangement of furnace; Fig. 7 is a section taken on line 7—7 of Fig. 6; and Fig. 8 is a section taken on line 8—8 of Fig. 6.

Referring first to Figs. 1 to 5, I illustrate therein a structure which may be generally composed of structural brick with an inner lining of fire brick and with a lining or bed of magnesite wherever desired. I build a structure which includes an inclined smelting chamber whose upper part forms an ore heating chamber 10 and whose lower part forms a melting chamber 11. There is a

baffle wall 12 between the two chambers 10 and 11; and the chamber walls converge toward the lower end so that the lowermost end of chamber 11 is smaller than any other part of the whole chamber. The floor 60 12 of these chambers slopes toward a center line as is shown in Fig. 2 and the roof 13 is arched. The floor of chamber 11 may be lined with magnesite or other material as indicated at 14, the floor being generally 65 lined with a lining of firebrick as indicated at 15 in Fig. 1, and the roof being also lined as indicated at 16. At the upper end of this sloping and downwardly contracting smelting chamber there is a charging opening 17 which may be fed from a hopper or any other suitable means.

At the upper end of the chamber 10 there are two openings 20, which lead into the upper ends of two regenerating chambers 75 21. These regenerating chambers 21 are preferably placed in a vertical position; although this is not necessarily the case and these chambers may be placed in horizontal or other position as is desired. However, for 80 the most preferred arrangement I place these regenerating chambers in vertical positions where the openings 20 from the upper rear end of the smelting chamber may communicate directly with the upper ends of the 85 regenerating chambers. These two regenerating chambers are built into the structure and are formed with inner surface linings of fire-brick or the like as shown at 22 and are divided by a wall 23 of like material. At their lower ends each of these regenerating chambers communicates with the rear end of the hot air tunnel 24 and also with a passage flue 25. The two passage flues lead to the bottom of stack 26 90 95 through which the heated gases of combustion, etc. are discharged to atmosphere. This stack may be of sufficient height to create the draft necessary to the successful operation of the device; or a forced draft 100 may be used if desired.

Passages 20 are controlled by doors 27 which are hung and operated in such a manner that when one of the doors is opened the other is closed. For instance, these two 105 doors may be hung on the ends of a cable 28 which passes over the sheaves 29 on shafts 30. These shafts 30 also carry sheaves 31 over which a cable 32 passes and on the ends of cable 32 hang doors 33 which control 110

the flue passages 25. Any suitable means may be used for operating these doors. For instance, all of them may be operated by merely moving one end of cable 32 up and down. Or a connection 32^a may be extended from one shaft 30 to a shaft with a crank 32^b in convenient operating position. In whatever manner the doors are operated, it will be seen that whenever one of the doors 10 of either pair is opened the other of that pair is closed; and it will be seen that the two doors 27 and 33 belonging to either regenerating chamber will be closed or opened at the same time. When one of these sets of doors 15 is open then the heated gases of combustion from the smelting chamber pass through the passage 20 and then pass downwardly through the brick checker work 35 in that regenerating chamber and then pass through flue passage 25 and through the stack. These gases heat the brick checker work to a high temperature; and when this has been done then the positions of the doors are reversed and then those doors 27 and 33 20 which have been opened are closed. At the same time air is admitted to the upper end of this regenerating chamber through the air pipe 36 controlled by any suitable valve, as indicated at 37. The two valves on the 25 two pipes 36 may be interconnected as indicated at 30 in Fig. 5 and so related that when one of them is opened the other is closed; and the action of the dampers may be made automatic by a driving connection 33^a between a damper and one shaft 30. When the two doors 27 and 33 are thus closed and air is admitted to the upper end of the regenerating chamber, this air then passes down through the heated brick 30 checker work and passes into the hot air flue 24 to its forward end. Near the forward end of the hot air flue there are air passages 40 which lead from the hot air flues to the sides of chamber 11; communicating with 35 the chamber 11 at the side wall of the chamber directly under the arch of the roof. These passages 40 are controlled by dampers or other means, as indicated at 41; and they are arranged so that with a plurality of 40 these passages there is provision for feeding air into the chamber 11 at different heights; so that by proper manipulation of the dampers, etc., the air may be blown in over the surface of the material in the chamber and 45 may be blown in at several points so as to come into thorough and intimate contact with all of the parts of the material. Adjacent the air openings into chamber 11 I may place burner openings 45, through 50 which burners 46 project flame into chamber 11. These burners preferably project their flame diagonally inwardly and downwardly into the chamber 11 so as to direct the flame somewhat downwardly along the length of

the chamber: These burners being in proximity to the air openings, draw their air from said openings, although some air for the burners may be drawn through the burner openings 45. The melted metal may be taken off at the metal tap 47 at the lower end of chamber 11 while slag may be removed through a side opening or openings 40. Rabble openings or doors may be provided as indicated at 49, for the usual purposes. 55

In the operation of the smelter furnace the ore is fed through openings 17 and the chambers 10 and 11 are kept substantially full of material. The ore is heated in chamber 10; and in this chamber it may be given a roasting treatment if so desired; or the whole treatment in the smelter may be that of reduction—deoxidation, etc. The heated ore passes downwardly over the floor of the chamber and under baffle wall 12 into chamber 11 where the metal is melted and accumulates in the lower end of the chamber. The slag on the surface of the melted metal may be drawn off through the slag taps from time to time. The operation in chambers 10 and 11 is continuous, the chamber being continuously supplied with heated air from one or the other of the regenerative chambers; while the regenerative chambers are alternately heated and cooled. However, in the form shown in Fig. 6 and following, I show a construction wherein there is only a single regenerative system which is kept in continuous operation. This single regenerative system may comprise a plurality of air pipes through which the air passes and around which the heated gases of combustion pass. For instance, two air pipes 50 and 51 may be set in the stack 26 and regenerating chamber 21. Air may be blown in at 52 at the low end of one of these pipes, preferably the one in the stack, passing upwardly through pipe 50 and thence through communication 53 and through the upper end of pipe 51 and then down and out through communicating pipe 53 into hot air tunnel 24^a. In this case there is only one hot air tunnel, as shown at 24^a; but otherwise the furnace construction may be substantially the same as that hereinbefore described. 115

In Fig. 6 I also show air pipe 55 through which air may be blown upwardly into stack 26 to create a forced draft upwardly through the stack.

If so desired, the baffle wall 12 may be hollow as at 12^a and a burner 46^a may extend into the baffle wall and project a flame through opening 45^a downwardly into the furnace chamber 11. The rabble openings at 49 may be placed in such position as to be at or near the surface of the pile of material in chamber 10—the material which is passing under the baffle wall. 120 125

Having described a preferred form of my invention, I claim:

1. In smelting furnaces, a structure having an elongated chamber in a sloping position and having a sloping roof forming the upper side of the chamber, means for feeding in ore at the upper end of the chamber, and heating means at the lower end of the chamber, said chamber contracting 10 in size toward the lower end and having a transverse baffle wall extending downwardly from its sloping roof across the central portion of the chamber.

2. In smelting furnaces, a structure having an elongated chamber in a diagonal sloping position and having a sloping roof forming the upper side of the chamber, said chamber contracting toward its lower end and having a transverse baffle wall depending 20 from the sloping roof near its center dividing it into an upper heating chamber and a lower melting chamber, means to admit air to the lower melting chamber, and burner means in connection with the melting chamber.

3. In smelting furnaces, a structure having an elongated chamber in a diagonal sloping position and having a sloping roof forming the upper side of the chamber, said chamber contracting toward its lower end and having a transverse baffle wall depending from the sloping roof near its center dividing it into an upper heating chamber and a lower melting chamber, means to 30 heat air and to admit the heated air to the lower melting chamber, and burners projecting flame into the lower melting chamber.

4. In smelting furnaces, a structure having an elongated chamber in a diagonal sloping position and having a sloping roof forming the upper side of the chamber, said chamber contracting toward its lower end and having a transverse baffle wall depending 40 from the sloping roof near its center dividing it into an upper heating chamber and a lower melting chamber, means to heat air and to admit the heated air to the lower melting chamber, and burners projecting flame into the lower melting chamber; outlet means for withdrawing melted metal and slag from the lower melting chamber.

5. In smelting furnaces, a structure embodying a diagonal sloping elongated chamber with a continuous sloping floor which contracts toward its lower end, a baffle wall across the upper part of the central portion of said chamber dividing the chamber into an upper or heating chamber and a lower 50 melting chamber, there being burner openings in the opposite side walls of the chamber and said burner openings projecting inwardly and diagonally along the length of the chamber, and means to admit air to the

lower melting chamber adjacent the burner 65 openings.

6. In smelting furnaces, a structure embodying a diagonal sloping elongated chamber which contracts toward its lower end, a baffle wall across the upper part of the central portion of said chamber dividing the chamber into an upper or heating chamber and a lower melting chamber, said burner openings projecting inwardly and diagonally downwardly along the length of 70 the chamber; a hot air tunnel substantially horizontal under the sloping chamber, the structure containing passages leading from the hot air tunnel upwardly and discharging into opposite sides of the chamber adjacent the burner openings and at points spaced vertically apart; and means heated by heat from the furnace to heat air to pass to the furnace through the hot air tunnel.

7. In smelting furnaces, a structure embodying a diagonal sloping elongated chamber which contracts toward its lower end, a baffle wall across the upper part of the central portion of said chamber dividing the chamber into an upper ore-heating 80 chamber and a lower melting chamber, burner openings into the lower melting chamber, said burner openings projecting inwardly and diagonally downwardly along the length of the chamber; a hot air tunnel substantially horizontal under the sloping chamber, the structure containing passages leading from the hot air tunnel upwardly 90 and discharging into opposite sides of the chamber adjacent the burner openings and at points spaced vertically apart; and means heated by heat from the furnace to heat air to pass through the hot air tunnel, said means embodying a pair of regenerating chambers with heat conducting means therein, and means to direct the heated gases of combustion from the upper end of the heating chamber through said regenerating chambers and means to direct air through 100 said regenerating chamber.

8. In smelting furnaces, a structure embodying a sloping or heating chamber, means for admitting ore at the upper end of said chamber and heating means at the lower end of said chamber, a horizontal hot air tunnel under said chamber, the structure having air passages between the end of said hot-air tunnel and the lower part of the chamber, and a vertical regenerating chamber at the higher end of said ore-heating 115 chamber and in communication at its upper end with said ore-heating chamber and at its lower end with said hot air tunnel.

9. In smelting furnaces, a structure embodying a sloping elongated chamber and 120 having a sloping roof which forms the upper side of the chamber, a baffle wall depending from the sloping roof across the

upper part of the central portion of the chamber dividing the chamber into two parts, means to feed ore into the upper part, means to project heating flame into the lower part, and means to deliver air into the lower part at points spaced apart along the length of the chamber.

10. In smelting furnaces, a structure embodying a sloping elongated chamber having a continuous sloping floor and having a sloping roof, and a baffle wall projecting downwardly from the sloping roof of the chamber into its central portion to divide the chamber into an upper heating chamber and a lower smelting chamber.

Copies of this patent may be obtained for five cents each, by addressing the "Commissioner of Patents, Washington, D. C."

11. In smelting furnaces, a structure embodying a sloping elongated chamber having a continuous sloping floor and having a sloping roof, and a baffle wall projecting downwardly from the sloping roof of the chamber into its central portion to divide the chamber into an upper heating chamber and a lower smelting chamber, the whole chamber contracting from its upper to its lower end.

25
In witness that I claim the foregoing I have hereunto subscribed my name this 27th day of June, 1918.

EDWIN E. RUSHTON.
